HYDRAULIC CONTAINER SEALING MEANS

Harry E. Stover, Lancaster, Ohio, assignor to Anchor Hocking Glass Corporation, Lancaster, Ohio, a corporation of Delaware

Application October 12, 1956, Serial No. 615,587

15 Claims. (Cl. 53—361)

The present invention relates to sealing machines for applying closures to containers and more particularly to such a machine embodying a hydraulic chuck or sealing head for applying a closure to a screw thread or lug-type container.

Screw-type closures are desirable on many types of packages and particularly on food containers such as ketchup, jam, or powdered coffee containers, where the user opens and reseals the container many times over a period of time. For such containers, a screw thread offers a practical closure fastening means as the closure is easily reapplied after the initial opening to provide a relatively airtight seal for the intervals between use.

One drawback with regard to screw closures exists in the relative difficulty encountered in the initial application of the closure on automatic sealing machines. Automatic sealing machines for use with screw closures have been unsatisfactory as they either use complex rotating chuck arrangements or they have hydraulic or mechanical closure shaping means adapted for use only on relatively thin and easily shaped closure shells.

It is known to fix screw-type closures on bottles by means of an apparatus in which a membrane is forced around the cap on the container neck by hydraulic force to press the cap into conformity with the container neck. The present invention provides an improved hydraulic device which will deform a selected portion of a closure to conform it to a container finish such as a threaded finish and which is capable of forming threads or lugs on a metal closure formed of heavy gauge metal.

Accordingly, an object of the present invention is to provide an improved sealing means for screw-type closures.

Another object of the present invention is to provide an improved hydraulically operated sealing machine.

Another object of the present invention is to provide a sealing means for screw-type closures adapted for high-speed operation.

Another object of the present invention is to provide an improved hydraulic sealing head for applying screw-type closures.

Another object of the present invention is to provide an improved hydraulic sealing head adapted for automatic sealing machines.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawings, forming a part of the specification, wherein:

Fig. 1 is an elevational view in section of a preferred embodiment of the sealing head showing the hydraulic and container handling connections diagrammatically;

2

Fig. 2 is an elevational view in section of the sealing head of Fig. 1 with the hydraulic pressure applied;

Fig. 3 is a perspective view of the resilient closure shaping ring;

5 Fig. 4 is a perspective view of a closure before it is threaded;

Fig. 5 is a perspective view of the closure of Fig. 4 after it has been shaped by the sealing head during the container sealing action;

10 Fig. 6 is a fragmentary sectional view of a sealing head mounted on a turret-type automatic sealing machine;

Fig. 7 is a sectional view of the sealing head of Fig. 6 with the hydraulic pressure applied;

15 Fig. 8 is a sectional view of the valve taken along line 8—8 of Fig. 6; and

Fig. 9 is a fragmentary view of another embodiment of the turret-type hydraulic sealing machine.

A preferred embodiment of the sealing head 1 comprising the hydraulic chuck 2 and the support means 4 therefor is shown in Figs. 1-3.

The cup-like hydraulic chuck 2 receives the mouth of a filled container 7 having an unthreaded closure 8 placed loosely thereon. While holding the washer 8a of closure 8 tightly against the mouth of the container 7, the chuck 2 squeezes closure 8 to form threads 11 therein (Fig. 2) which are complementary to container threads 10 so that the closure 8 is fastened onto and seals the container 7.

30 The support means 4 for chuck 2 comprises a suitable rod 5 connected by threads 6 to the hydraulic chuck 2 and mounted on a suitable holder (not shown).

In Fig. 1, a vertically reciprocal container support 12 is shown which is used to raise the top of the container 7 within the hydraulic chuck 2 after the closure 8 has been placed on the container 7. If desired, the container may be placed on a stationary support and the hydraulic chuck support means 4 may be reciprocated vertically onto the container 7. Closure 8 may also be inserted

40 into the hydraulic chuck 2 rather than being placed on the container mouth if desirable.

The hydraulic chuck 2 comprises a closure sealing member 14 threadedly connected at its top by threads 6 to the rod 5 and having an annular body member 15 mounted thereon. A resilient closure shaping means 16 is held in place between the closure seating member 14 and the body member 15 by a cap 17 threadedly connected to the body member 15.

The closure shaping means 16 is formed of a resilient material such as rubber and it has a radially inwardly extending closure shaping flange 19 in its hollow center portion 20. An annular aperture 21 is provided within the body of shaping means 16 encircling the flange 19 and adapted to be filled with hydraulic fluid under pressure.

55 The hydraulic fluid expands the aperture 21 to cause the shaping means 16 to expand inwardly into the hollow center portion 20 so that its shaping flange 19 engages the closure 8 on container 7. Sufficient hydraulic pressure is applied within the aperture 21 so that the flange 19 forces the closure skirt 9 inwardly against the threads 10 on the top of the container 7 to form the thread 11 on the closure 8 which is complementary to the container thread 10. Fig. 4 shows the general shape of a suitable closure cap 8 before the formation of the threads 11

60 and Fig. 5 shows the closure threads 11 formed by the squeezing action of flange 19. The resilient shaping means 16 in its preferred form is held in position in the hydraulic chuck 2 by outer and inner flanges 22 and 23, respectively, formed at the upper edge of the shaping means 16. The inner flange 23 is tightly gripped between corner 24 on body member 15 and a locking flange 25 on the closure seating member 14. The outer flange 22

is locked between corner 26 in the body member 15 and a locking ring 27 held in place by the cap 17. The upper portion of the aperture 21 in the resilient shaping means 16 is left open so that it communicates with an annular hydraulic fluid conduit 28 formed in the body member 15. Conduit 28 distributes the hydraulic fluid to the aperture 21 in the closure shaping means from a suitable inlet port 29.

In order to limit the expansion of the resilient closure shaping means 16 to a radially inwardly directed motion of the flange 19, the top and bottom portions 30 of the shaping flange 19 are confined between the spaced extremities 31 and 32 of the closure seating member 14 and the cap 17, respectively. Thus, all the outer surfaces of the resilient shaping means 16 are confined against expansion with the exception of the shaping surface 34 of the shaping flange 19. When hydraulic fluid under pressure is admitted through the conduit 28 into the aperture 21 of the shaping means 16, the shaping flange 19 is forced radially inwardly against the skirt 9 of the closure 8 as seen in Fig. 2, thereby shaping a cylindrical portion of the skirt so that it conforms to the threads 10 on the container 7. By providing the inwardly extending shaping flange 19 and by controlling its deformation with the spaced extremities 31 and 32, the shaping force on the closure 8 is concentrated in the particular area desired so that the thread is formed in the particular portion of the skirt desired. Also, by limiting the shaping area to a relatively narrow portion of the closure skirt, it is possible to form threads in closures formed of relatively thick metal quickly and effectively without distorting the remaining unthreaded portions of the closure.

In addition to forming threads on the closure skirt, it is also desirable in many instances to form a step or groove at the outer edge of the upper surface of the closure to reinforce the closure and to move the closure gasket 8a tightly against the sealing finish of the container mouth. A shaping flange 36 is provided on the lower contacting surface of the closure seating member 14 to perform this shaping operation. When the hydraulic chuck 2 receives the closure 8 atop container 7, chuck 2 and container 7 are moved together with sufficient force so that the flange 36 of the closure seating member 14 shapes the top 37 of the closure to provide the step 38 at the edge of closure top 37 as seen in Fig. 5.

In order to assist in separating the hydraulic chuck 2 from the sealed container 7 after the threading operation is completed, an ejector rod 40 is provided in the closure seating member 14. Ejector rod 40 is slidably mounted in a suitable bearing 41, and it is urged downwardly against closure 8 by coil spring 42. The downward travel of the ejection rod 40 is limited by a suitable stop nut 44.

Any suitable means may be used to supply hydraulic fluid under pressure to the aperture 21 of the shaping means 16 after the hydraulic chuck has been lowered into place onto the container 7. In Fig. 1 a hydraulic cylinder 45 is shown connected by a hydraulic line 46 to the inlet port 29. A rotating cam 47 turned by hand or by a suitable drive mechanism intermittently raises the piston 48 of the hydraulic cylinder 45. The rotation of cam 47 may be synchronized with the operation of the container support 12 by a suitable connecting means (not shown) to cause the piston 48 to be raised to apply pressure for a predetermined period to the shaping means 16 while the container support 12 is in its raised position.

Another embodiment of the sealing head is shown in Figs. 6-8 which is adapted for being mounted on a turret-type sealing machine such as is disclosed in the United States Patent No. 2,610,779, owned by the assignee of the present invention. The sealing machine disclosed in Patent No. 2,610,779 has a rotating turret containing a plurality of spaced sealing heads which are intermittently lowered over the mouths of containers traveling on a circular conveyor located beneath and moved in

5 synchronism with the sealing heads. Fig. 6 shows one such sealing head 50 having a hydraulic chuck 51 mounted on its lower end in accordance with the present invention. Sealing head 50 is attached to the outer edge of the rotatable sealing turret 52 in place of the sealing heads shown in the above-mentioned patent. As the turret 52 is rotated above containers 54 being moved therebelow by a suitable conveyor as described in the above patent, sealing head 50 is alternately lowered by 10 the cam 71 and raised by the cam 60. When the sealing head 50 has lowered the hydraulic chuck 51 over the mouth of the container 54, a closure 66 is forced tightly against the container mouth and is sealed thereon by the squeezing action of the hydraulic chuck 51, as will be 15 more fully described below.

The sealing head 50 comprises an outer casing 55 bolted to the turret 52 and an elongated hollow member 56 slidably mounted therein on bearings 57 for vertical movement with respect to the turret 52. The lifting of 20 the elongated hollow member 56 within the outer casing 55 is controlled by a cam roller 58 rotatably mounted on the hollow member 56 on pin 59. When the hydraulic chuck 51 is to be raised clear of the container 54, the cam roller 58 engages the upper surface of a cam 60 which is fixedly mounted on the turret shaft 61 and which is shaped to raise the hydraulic chuck from the container after the shaping action. A coil spring 62 mounted between the lower end 64 of the outer casing 55 and flange 65 on the lower end of hollow member 56 urges the hollow member 56 downwardly and urges the cam roller 58 towards cam 60.

In order to move the sealing head 50 downwardly against the closure 66 on the container 54 with sufficient force to provide a tight seal, an elongated rod 67 is slidably mounted on suitable bearings 68 within the hollow member 56. A cam roller 69 is mounted on a suitable shaft 70 at the top of the rod 67 and it engages the lower surface of a circular cam 71, which is fixedly mounted on the turret shaft 61. Cam 71 lowers the rod 67 and attached hydraulic chuck 51 against the force of a coil spring 72, which is compressed between the cam wheel bracket 74 at the upper end of rod 67 and the top 75 of the outer casing 55. The hydraulic chuck 51 is mounted upon the lower ends of both the rod 67 and the hollow member 56, as will be described more fully below, so that the chuck 51 is moved upwardly by the combined action of cam roller 58 on cam surface 60 and the coil spring 72 and is moved downwardly by the combined action of cam roller 69 on cam 71 and cam spring 62. As seen in Fig. 6, when the hydraulic chuck 51 is forced downwardly against the closure 66 by cam 71 and cam roller 69, the cam 60 is shaped to clear cam roller 58 so that cam 60 does not impede the lowering of the hydraulic chuck 51. Similarly, cam 71 terminates before the cam 60 raises the hydraulic chuck 51 clear of container 54 so that cam 71 does not interfere with the raising of the hydraulic chuck 51.

The hydraulic chuck 51 is shown in detail in Fig. 7. The hydraulic chuck 51 comprises a closure sealing member 80 threadedly connected to rod 67 at its top by threads 81 and having an annular body member 82 mounted thereon. A resilient closure shaping means 84 is held in place between the closure sealing member 80 and the body member 82 by a cap 85 threadedly connected to the lower portion of the body member 82. Closure shaping means 84 is formed of a suitable resilient material such as rubber in generally the same manner as the above-described closure shaping means as illustrated in Fig. 1. Closure shaping means 84 as illustrated in Figs. 6 and 7 is a different embodiment from the resilient shaping means 16 illustrated in Fig. 1 as its annular closure shaping flange 86 is located centrally of the hollow inner portion of the shaping means and as its mounting flanges 87 and 88 are mounted at the top and bottom, respectively, of its outer surface. The closure shaping means 84 is held

in position between the closure shaping member 80 and the cap 85 by an annular retaining ring 89 which has inwardly directed upper and lower flanges 90 and 91, respectively, which engage the upper and lower flanges 87 and 88 of the closure shaping means and hold them in position against the closure sealing member 80 and the cap 85. The annular retaining ring 89 and the closure shaping means 84 cooperate to form an annular hydraulic channel 92 surrounding the central portion of the closure shaping means 84 and its inwardly directed closure shaping flange 86. Channel 92 communicates with a hydraulic inlet port 93 through an annular hydraulic distribution channel 94. Thus, after the hydraulic chuck 51 is lowered over the top of a container 54 with a closure 66 in place thereon, the admission of fluid under pressure to the channel 92 causes the central portion 95 of the closure shaping means 84 to move inwardly toward the retaining surfaces 96 and 97 of the closure sealing member 80 and the cap 85, respectively, and also causes the closure shaping flange 86 to simultaneously move inwardly against the skirt 98 of the closure 66 to press it against the threads 99 on top of the container 54. Threads 100 are formed on skirt 98 of closure 66 to fasten the closure 66 in sealing position on the container 54. When the hydraulic pressure is released by the hydraulic control system, which will be more fully described below, the resilient closure shaping means 84 resumes its original shape as seen in Fig. 6, allowing the hydraulic chuck 51 to be raised vertically above the top of the sealed container 54. Ejector rod 101, which is slidably mounted in a suitable bearing 102 in the closure sealing member 80, is urged downwardly by coil spring 104 to help separate the closure cap 66 from the chuck 51. The downward travel of the ejector rod 101 is controlled by a nut 105.

In the sealing machine disclosed in the above-mentioned Patent No. 2,610,779, a closure feed means is disclosed which supplies the closures to the sealing heads prior to the lowering of the sealing heads 50 onto the containers 54. The sealing means shown in Patent No. 2,610,779 presents the closures to the sealing head in such a position that the closure is drawn upwardly into the lower portion of the sealing head by a magnet mounted therein. A magnet 106 is provided in the ejector rod 101 of the hydraulic chuck 51 of the present invention for this purpose. Where the closures 66 are made of steel or another magnetic substance, the magnet 106 draws the closure 66 upwardly into the hydraulic chuck 51 in the same manner as disclosed in the Patent No. 2,610,779 prior to the lowering of the hydraulic chuck 51 over the top of the container 54. If desired, the cap 66 may be inserted in hydraulic chuck 51 by hand or applied directly to the container 54 rather than to the hydraulic chuck 51 prior to the lowering of the chuck 51 over the top of the container. Closure 66 may be placed on the container top by hand or by a suitable automatic closure applying means such as is shown in Patent No. 2,618,424, which is assigned to the assignee of the present invention.

During the rotation of the sealing turret 52 about its central stationary mounting shaft 61, it is desirable to have the hydraulic shaping fluid automatically applied to the hydraulic chuck 51 for a predetermined interval while the chuck 51 is lowered by cam 71 into sealing engagement with the closure 66 on container 54. A preferred embodiment of an automatic hydraulic control means or valve 110 is shown in Figs. 6 and 8. Valve 110 comprises a lower annular connector ring 111 fixedly mounted by bolts 112 to the turret shaft 61 and having an annular upper surface 114 in sliding engagement with an annular rotating ring 115 which is connected to the rotating turret 52. As seen in the sectional view in Fig. 8, the connector ring 111 has an elongated channel 116 therein which is connected to a source of hydraulic fluid under pressure by a line 117. The rotating ring 115 has a series of spaced connector ports 118, each one of which is coupled to one of the hydraulic chucks 51 by a flexible conduit 119. When the port 118 is moved into com-

munication with the channel 116 by rotation of the turret 52, hydraulic fluid from the line 117 flows into the hydraulic channel 92 of the hydraulic chuck 51 through channel 116, port 118, line 119, inlet port 93, and distribution channel 94. During the portion of the rotation of the turret 52 in which the port 118 is above channel 116, the hydraulic pressure of source 117 is applied to the closure shaping means 84 to perform the above-described shaping operation. After the port 118 passes beyond the channel 116, it moves above a release channel 120 in connector ring 111 which is connected by a line 121 to a hydraulic fluid reservoir at atmospheric pressure, allowing the pressure within the hydraulic channel 92 to return to normal and allowing the closure shaping means 84 to assume its normal position as shown in Fig. 8.

In place of the hydraulic control means 110, a separate hydraulic pressure means may be provided for each sealing head 50, as shown in Fig. 9. Thus, a hydraulic cylinder 130, similar to cylinder 45 of Fig. 1, is mounted for rotation with the turret 52 on each sealing head 50 and is hydraulically connected to the hydraulic chuck 51 by line 131. The piston 132 of the hydraulic cylinder is moved by a suitable cam surface 133 fixedly mounted on the turret shaft 61 so that the piston 132 is moved downwardly into the hydraulic cylinder 130 during the desired portion of the sealing head's movement about shaft 61 to apply shaping pressure to the hydraulic chuck 51.

The operation of the hydraulic chuck illustrated in Figs. 1 through 3 which has been described in connection with the above descriptions may be summarized as follows:

Container 7 is first placed on a suitable container support 12 with a closure 8 loosely positioned on its top. Thereafter, the container support 12 is raised to move the upper portion of the container 7 together with the cap 8, which is seated thereon, into the hydraulic chuck 2 of the sealing head 1. As seen in Fig. 1, the closure 8 is now positioned within the hollow center portion of the cup-like hydraulic chuck 2, and the lower portion of the skirt which is adjacent to the threads 10 on the closure 40 finish is positioned opposite the resilient closure shaping means 16 within the hydraulic chuck 2. The container support 12 forces the container 7 and closure 8 thereon upwardly against the closure seating member 14 with sufficient force so that the washer 8a is tightly seated against the mouth of the container 7 and so that shaping flange 36 of the closure seating member 14 forms the step 38 at the outer edge of top 37 of the closure 8. While the closure 8 is held tightly against the closure seating member 14, the cam 47 is rotated to move piston 48 upwardly, thereby forcing hydraulic fluid into the aperture 21 of the resilient closure shaping means 16 to force the shaping flange 19 tightly against the skirt 9 of closure 8 so that it is forced against the threads 10 of the container to form complementary threads 11. Threads 11 engage the threads 10 of the container 7 and hold the closure 8 tightly in place on the container 7 in sealing position. Thereafter, further rotation of cam 47 lowers piston 48 to release the hydraulic pressure on the shaping flange 19 so that the resilient closure shaping means 16 returns to its normal shape as seen in Fig. 1 and so that the container support 12 may be lowered to remove sealed container 7 from the hydraulic chuck 2. Ejector rod 40 moves downwardly under the force of coiled spring 42 to assist in the withdrawal of the closures 8 from the hydraulic chuck 2. Container 7 is now sealed with threaded closure 8 which may be removed and reapplied as desired by the consumer of the product packed in container 7.

The operation of the embodiment of the hydraulic chuck shown in Figs. 6 through 8 on a rotating turret-type sealing machine such as that disclosed in Patent No. 2,610,779 may be summarized as follows.

Sealing heads 50 as seen in Fig. 6 are mounted in spaced relation on a rotating turret as disclosed in the above-mentioned patent. During the initial portion of

the turret rotation, a cap feeder as shown and described in the above-mentioned patent supplies a closure 66 to the hollow cup-like hydraulic chuck 51 mounted on the bottom of each of the sealing heads 50. Further rotation of the sealing heads 50 by the turret 52 brings the hydraulic chuck 51 above a filled container 54 carried by a suitable table or conveyor on a path directly beneath the circular path of the sealing head 50. Further rotation of the sealing head 50 now brings its cam roller 69 into contact with the circular cam 71 thereabove which lowers the hydraulic chuck 51 onto the container 54 so that the closure 66 is positioned on the top of container 54 with its sealing washer 66a tightly pressed against the container mouth. During this portion of the turret rotation, cam 60 is shaped so that it passes below the cam roller 58 so that the cam roller 58 does not interfere with the downward motion of the sealing head 50. Additional rotation of the turret next brings the connector port 118 into communication with the hydraulic channel 116 in the connector ring 111 of valve 110 so that hydraulic fluid under pressure is admitted through line 119, port 93, and distribution channel 94 to hydraulic channel 92. The hydraulic fluid under pressure in channel 92 forces the closure shaping flange 86 of the closure shaping means 84 inwardly against the skirt 98 of the closure 66 and forces the skirt 98 against threads 99 of the container finish to form threads 100 on the closure 66. Additional rotation of the turret brings the connector port 118 above the release channel 120 in the connector ring 111 of the hydraulic valve 110, thereby releasing the hydraulic pressure on the shaping means 84 so that it returns to its normal position as seen in Fig. 6. Thereafter, cam 60 engages cam roller 58 to raise the sealing head 50 clear of the sealed container and the sealed container is carried out from under the turret 52 to a suitable unloading station. Circular cam 71 terminates before the cam 60 engages cam roller 58 so that cam roller 69 will not interfere with the raising of the sealing head 50 by cam roller 58.

In the embodiment shown in Fig. 9, the hydraulic shaping pressure in each hydraulic chuck 51 is applied by the downward movement of piston 132 under the control of cam 134 at the desired portion of the turret rotation.

It will be seen that an improved hydraulic chuck is provided which is relatively simple in form and which is, at the same time, effective in sealing containers by forming screw threads in closures applied to container tops. The hydraulic chuck disclosed is adapted for use on automatic sealing machines and provides a means for sealing screw-type containers simply and effectively and at high speeds. The hydraulic chuck of the present invention is also useful on closures formed of relatively heavy-gauge metal, and the molding operation of the chuck may be confined to predetermined relatively narrow portions of the closure skirts where it is desired to provide deep screw threads over a narrow portion of the container skirt to form an attractive and effective screw-type seal. The hydraulic chuck of the present invention is also readily adjusted to handle screw closures of varying shapes and sizes and thread patterns by a relatively simple exchange of a few of its elements.

As various changes may be made in the form, construction and arrangement of the parts herein without departing from the spirit and scope of the invention and without sacrificing any of its advantages, it is to be understood that all matter herein is to be interpreted as illustrative and not in a limiting sense.

Having thus described my invention, I claim:

1. In a sealing machine having a rotating turret with a plurality of sealing heads mounted thereon, the combination of a cup-like member on each of said sealing heads having a resilient hollow shaping means therein adapted to embrace a closure and to squeeze it into conformity with a container finish when subjected to hydraulic pressure, said resilient hollow shaping means

having a ring-like inner portion extending radially inwardly of said cup-like member, an annular conduit encircling said inner portion of said resilient hollow shaping means and connected to a hydraulic supply means, a hydraulic supply means comprising a control member adapted for connection to a source of hydraulic fluid under pressure and operatively connected to the turret to periodically connect the source of hydraulic fluid to the annular conduit of one of said resilient hollow shaping means for a portion of the turret's rotation.

2. In a sealing machine having a rotating turret with a sealing head mounted thereon, the combination of a cup-like member on said sealing head having a resilient hollow shaping means therein adapted to embrace a closure and to squeeze it into conformity with a container finish when subjected to hydraulic pressure, a hydraulic supply means comprising a control member adapted for connection to a source of hydraulic fluid under pressure and operatively connected to the turret to periodically connect the source of hydraulic fluid to said resilient hollow shaping means, said control member comprising a stationary member, a movable member connected to said turret for rotation therewith, said stationary and movable members each having a contact surface, said contact surfaces being in sliding engagement with one another, a first aperture on the contact surface of the stationary member adapted for connection to a source of hydraulic fluid under pressure, and a second aperture on the contact surface of the movable member adapted for connection to the resilient hollow shaping means and positioned to communicate with the first aperture for a predetermined portion of its travel over the contact surface of said stationary member.

3. The sealing machine as claimed in claim 2 in which one of said apertures comprises a channel having an elongated shape in the direction of travel of the other aperture whereby hydraulic fluid from the source is admitted to the hollow shaping means for a period proportional to the length of said channel.

4. In a sealing machine having a rotatable turret, the combination of a hollow hydraulic member mounted on said turret and having a resilient annular shaping means mounted therein, a conduit in said hydraulic member encircling at least a portion of said resilient annular shaping means, a hydraulic pressure generator mounted on said turret and hydraulically connected to said conduit, and actuator means operatively connected to said hydraulic pressure generator to actuate it for a portion of the turret rotation to subject said conduit and said shaping means to hydraulic pressure.

5. The sealing machine as defined in claim 4 in which said hydraulic pressure generator comprises a pump having a piston operatively engaging a stationary piston control cam on said sealing machine whereby rotation of said turret moves said engaging portion of said piston along said cam.

6. A sealing head for a sealing machine comprising the combination of a cup-like hydraulic chuck, a resilient shaping member mounted within said hydraulic chuck encircling the cavity therein and having a ring-like inner portion extending radially inwardly of said cavity, an annular conduit encircling said inner portion of said resilient shaping member and adapted for connection to a source of fluid under pressure whereby the admission of fluid under pressure into said conduit forces said inner portion of said shaping member radially inwardly of the hydraulic chuck cavity.

7. The sealing head as claimed in claim 6 in which said ring-like inner portion of said shaping member comprises a radially directed flange having radially directed top and bottom portions, and said hydraulic chuck has spaced extremities engaging said top and bottom portions to limit the flange to movement in a radial direction.

8. A hydraulic chuck for a sealing machine comprising the combination of a resilient annular shaping member

having a shaping flange on its inner surface extending radially inwardly thereof, spaced mounting flanges on said annular shaping member, a mounting means for said shaping member adapted to engage said flanges to mount said annular shaping member and to form a conduit therewith, and a hydraulic port in said mounting means communicating with the conduit at one end and adapted for connection to a source of hydraulic fluid at its other end.

9. A hydraulic chuck for a sealing machine comprising the combination of a resilient annular shaping member having a shaping flange on its inner surface extending radially inwardly thereof, an annular channel in said shaping ring spaced outwardly from said shaping flange and extending substantially coextensively therewith in an axial direction, mounting flanges on opposite edges of said channel, a mounting means for said shaping member adapted to engage said flanges and to close off said annular channel to form a conduit therewith, and a hydraulic port in said mounting means communicating with said conduit at one end and adapted for connection to a source of hydraulic fluid at its other end.

10. A sealing head for a sealing machine comprising the combination of a cup-like hydraulic chuck having a cavity adapted to fit over a closure shell on the mouth of a container, an annular aperture in said hydraulic chuck encircling the cavity and having a ring-like portion in communication therewith, a resilient shaping member in said aperture and occupying the ring-like portion of said aperture communicating with the cavity, a shaping flange on the resilient shaping member extending radially inwardly of the chuck cavity, and said aperture adapted to communicate with a source of fluid under pressure whereby the admission of fluid under pressure into said conduit forces the shaping flange of said shaping member radially inwardly of the hydraulic chuck cavity against the closure shell.

11. The sealing head as claimed in claim 10 which further comprises a closure seating member positioned above the cavity in the hydraulic chuck and adapted to contact the closure top to hold the closure tightly against the container mouth.

12. The sealing head as claimed in claim 11 in which said closure seating member has a shaping flange on its surface adapted to shape the closure top.

13. A resilient shaping member for a hydraulic chuck 10 comprising a resilient annular body member having a radially directed shaping flange on its inner edge and having spaced ring-like mounting flanges outwardly of said shaping flange adapted for engagement with mounting flanges on the hydraulic chuck to fasten the shaping member thereto and to form a conduit between the body portion and the hydraulic chuck.

14. The resilient shaping member as claimed in claim 13 in which said body member has a U-shaped cross section and said mounting flanges are positioned at the 20 opposite top edges of the body member.

15. The resilient shaping member as claimed in claim 13 in which said spaced mounting flanges are located at the top and bottom of the outer edge of said body member.

25 16. The resilient shaping member as claimed in claim 13 in which said spaced mounting flanges are located at the top and bottom of the outer edge of said body member.
